SHEAVE

David Firth, South Bend, and Donald P. Lower, Mishawaka, Ind., assignors to Dodge Manufacturing Corporation, Mishawaka, Ind., a corporation of Indiana

Application August 6, 1942, Serial No. 453,830

9 Claims. (Cl. 74—230.10)

This invention, pertaining to sheaves, has been evolved in an effort to further the national campaign of conservation of metals. In the present emergency it becomes important to conserve cast iron in addition to other metals. This invention contemplates effecting a substantial saving of metal by the utilization of wood or other suitable non-metallic material for the construction of sheaves for multiple V-belt drives and other machinery drives of the belt and sheave type.

A feature of the invention is the provision of a non-metallic sheave with practicable means for securing it to the sheave shaft, this being of importance for a non-metallic sheave of the block type or of the type having a non-contractible hub. Another feature is the provision of a laminated wood sheave body of advantage with respect to disposition of the grain of the wood and also of special advantage for a long sheave having a plurality of belt grooves in an overhanging portion which extends beyond the end of the motor shaft on which the sheave is mounted. With respect to the last mentioned feature, the invention is also applicable to a wood sheave of the web type having an extending rim portion provided with such grooves.

Cast iron sheaves of the block type are used extensively in multiple V-belt drives. The invention has particularly in contemplation the production of wood sheaves in the same forms and sizes as such cast iron sheaves. The invention aims to provide strong and efficient structures of practicable character, susceptible of economical manufacture and serviceable for duties for which such cast iron sheaves are commonly employed.

Illustrative embodiments of the invention in block type sheaves for multiple V-belt drives are shown in the accompanying drawings, in which:

Fig. 1 is a central longitudinal section of one form of sheave embodying the invention.

Fig. 2 is a view thereof partly in end elevation and partly in cross section taken on the line 2—2 of Fig. 1.

Fig. 3 is a cross section taken on the line 3—3 of Fig. 1.

Fig. 4 is a central longitudinal section of a sheave similar to that of Fig. 1 and embodying additional features.

Fig. 5 is a central longitudinal section of a sheave differing from the others in its form and body construction but embodying in common with the others the novel means herein disclosed for securing the sheave to its shaft.

In Figs. 1, 2, and 3, a non-metallic sheave body is represented by a block 15 of annular cross

section composed of adhesively united wood plies or laminations, preferably of hard wood such for example as hard maple, these plies or laminations being arranged parallel with the sheave axis and extending from end to end of the sheave body. The several wood plies or laminations composing the sheave body are designated in the drawings by the reference numerals 1 to 14 respectively. Annular belt grooves formed in the periphery of the sheave body are designated by the numeral 16. In this instance the central bore of the sheave body is of two diameters as indicated at 17 and 18. The portion of the bore of greater diameter is referred to as the hub bore. Fitted therein is a wood bushing 19 through which the sheave body is supported on a motor shaft 20. It will be observed that a plurality of the belt grooves 16 are in an overhanging portion of the sheave body which extends beyond the end of the motor shaft. Such overhanging portion of the sheave body is subjected to bending and shearing forces imposed by the tension of the belts which engage the grooves in such overhanging portion. In this connection the described structure of the sheave body is of particular advantage. Not only does it give the great strength of a laminated wood structure, but also, by virtue of the arrangement of the wood plies or laminations, there is no transverse joint which must sustain the load imposed by the tension of the belts on the overhanging portion of the sheave body. All of the belts concurrently engage the same wood components, which tends to equalize stresses in the sheave body throughout its length, and the belt tension on the portion of the sheave which is centrally supported on the wood bushing 19 helps to support the overhanging load.

By constructing the sheave body of wood plies or laminations arranged parallel with the axis and having the grain of the wood running longitudinally of the body or transversely of the V-grooves of the peripheral portion thereof, a further important result is obtained, namely that the surfaces of the side walls of the V-grooves are cut across the grain of the wood, giving hard durable wear surfaces for engagement by the driving belts.

In the illustrative structure, the outermost wood plies or laminations 1 and 14 are of greater thickness at their medial portions than the depth of the belt grooves 16, the intermediate laminations 2 to 13 inclusive being of less thickness. It will be observed that there are no planes of joinder of the wood laminations only through the side walls of the belt grooves. In other words,

all planes of joinder of the wood laminations pass through the portion of the wood body which is within an imaginary cylinder represented by the bottoms of the belt grooves. Hence corresponding portions of the side walls of all the belt grooves are integral with each other or in the same wood components.

Still another advantage of the sheave body construction described is that it can be easily and inexpensively made by cutting and forming it from a pile of adhesively united wood plies or sheets.

The wood bushing 19 is of the solid type as distinguished from a split contractible bushing. In other words, it consists of an unsplit non-contractible wood bushing fitting the hub bore and fitting the shaft to which the sheave is mounted. Sheaves of different sizes or pitch diameters embodying the invention, within certain ranges of pitch diameters, are intended to be made with hub bores all of the same diameter and to be equipped with wood bushings to fit different shaft sizes; enabling dealers and also the manufacturer to carry in stock a relatively small number of each of the different sizes of sheaves and a relatively large quantity of wood bushings to fit all of said sheaves and to adapt them to different shaft sizes; thus minimizing the quantity of sheaves of different pitch diameters which need to be carried in stock.

The wood bushing 19 is formed with an internal longitudinal keyway 21 in which fits a shaft key 22 by which the bushing is keyed to the shaft. The key 22 is a conventional metal shaft key such as is ordinarily used for keying a cast iron sheave to the shaft. The wood bushing is also formed with an external longitudinal groove 23 angularly spaced from the keyway 21; said groove 23 being engaged by a metallic element embedded in the wood sheave body for keying the shaft body to the bushing.

The wood sheave body is secured to the sheave shaft by set screws 24 and 26 extending through and in threaded engagement with nuts 25 and 27 fitted in recesses therefor in the wood sheave body, with the screw holes of the nuts in alignment with radial set screw holes in the body. Said set screws extend through registering holes therefor in the wood bushing 19 and bear one against the shaft key 22 and the other directly against the shaft. The nut 27 carrying the set screw 26 constitutes the element previously referred to engaging the external longitudinal groove 23 of the bushing. It will be understood that the tightening of these set screws against the shaft draws the sheave body toward the shaft in a direction opposite the force or resultant of forces applied by the set screws, thereby rigidly clamping the wood bushing 19 between the shaft and the sheave body. Such clamping could be effected with either a single set screw or a pair of set screws arranged at an angle of substantially less than 180 degrees apart. The use of two set screws so arranged distributes the clamping action and provides a more effective fastening, with less distortion of parts, than would be obtainable with the use of a single set screw. The most reliable clamping action with least distortion of parts results from the use of two set screws arranged with their radial centers at an angle of 120 degrees. The set screws 24 and 26 in the illustrative sheave are therefore so arranged, the positions of the nuts 25 and 27 and the relationship of the keyways 21 and 23 of the

bushing being in accordance with such arrangement.

The nuts 25 and 27 are provided in the form of metal elements of round cross section having transverse threaded holes for engagement by the set screws. These elements, arranged adjacent to and parallel with the hub bore, are fitted in recesses therefor formed in the wood hub body simply by drilling holes therein from its rear end. After the nuts are inserted in the nut holes, these holes may be closed by wood plugs as indicated at 28. This feature of the invention is a substantial factor in economy of construction of the sheave, since the recesses for the nuts can be easily formed by simply drilling holes parallel with the hub bore. Further, this feature is important from the constructional standpoint, particularly in the case of a wood or other non-metallic sheave body of small radial thickness between the hub bore and the bottoms of the belt grooves. It will be observed that the diameter of the cylindrical metal elements constituting the nuts is only about twice the diameter of the set screws. Therefore the nuts occupy but little space in the cross section of the sheave body, as compared with the space that would be occupied by nuts of ordinary form; and in a sheave body of small radial thickness there may be a substantial radial thickness thereof around the nuts. Moreover, due to the cylindrical form of the nuts they bear outwardly for half of their surfaces, and also bear laterally for half of their surfaces, in the surrounding wood body. The nuts may be considered as embedded in the sense that they are closely fitted in the surrounding wood body and firmly supported thereby against forces tending to displace the nuts, due to the driving of the set screws against the shaft and the driving of the sheave body either by the shaft against the load on the belts or by the belts against the load on the shaft.

The fastening devices consisting of the nuts and set screws above described may be duplicated so as to have two set screws bearing on the shaft key and two others bearing directly against the shaft, as may be desirable in long sheaves having a large number of belt grooves, say ten or more. Such a construction is shown in Fig. 4.

In Fig. 4 the laminated wood body 15^a is identical to that first described except that its annular ribs 29 at the ends of the body are thinner than in the first construction, and in order to protect these end portions from chipping the sheave body is provided with adhesively affixed wood caps 30. Fitted in the hub bore of the sheave body 15^a is a wood bushing 19^a identical to that first described. The longitudinal keyway in said bushing for engagement with a shaft key is indicated at 21^a. The sheave body is provided with means for securing it to the shaft identical to the means first described except that the fastening devices are duplicated, there being two set screws 24^a extending through and in threaded engagement with the embedded nuts 25^a and screwable against the shaft key (not shown), and two set screws 26^a extending through and in threaded engagement with the embedded nuts 27^a and screwable directly against the shaft. The two pairs of set screws 24^a and 26^a are angularly spaced 120 degrees from radial center to radial center, and the cylindrical metal elements constituting the nuts 27^a protrude laterally into the hub bore of the sheave body and engage an external hub groove (not shown) of the wood bushing 19^a, as in the first described construction. The cylindrical

metal elements constituting nuts 25^a and 27^a are fitted in holes drilled in the wood sheave body parallel with the wood sheave shaft, the nuts of each pair being spaced by wood plugs 31 fitted in said holes, and the holes being plugged therein by wood plugs 28^a.

Fig. 5 shows a wood sheave comprising a laminated wood body 15^b fitted with a wood bushing 19^b and having means for securing it to the sheave shaft comprising set screws 24^b and 26^b engaging nuts 25^b and 27^b. With respect to the wood bushing and means for securing the sheave body to the shaft, the construction is identical to that first described, but the wood sheave body is of different form and construction from the others, being composed of adhesively united wood discs 32 and end caps 33. The belt grooves 16^b are provided by forming adjacent discs 32 with confronting marginal beveled portions forming the side walls of said grooves. A sheave body of this type may be made by adhesively joining pre-formed wood components. This body construction has certain advantages and is practicable for sheaves centrally supported through the bushing on the shaft for its full length or nearly its full length and having only a short overhanging portion.

Sheaves embodying the invention are of strong and sturdy character, of practicable and efficient construction, susceptible of economical manufacture, easily installed, and serviceable under many conditions for duties for which the cast iron sheaves of corresponding sizes are commonly employed. The invention therefore offers opportunity for extensive utilization of wood in the construction of sheaves for multiple V-belt drives and other belt and sheave type drives, as well as for replacement of existing cast iron or other metallic sheaves by wood sheaves embodying the invention, with resultant release of much valuable metal for other essential purposes.

Though hard wood is considered the most satisfactory material, it is apparent that sheave bodies of the constructions described can be made as laminated bodies of fiber board or other suitable non-metallic material having the strength, hardness, toughness and cohesiveness suitable for sheave body constructions, considering the duties to be imposed on the sheaves. The means provided by the invention for securing the sheave body to the sheave shaft is also applicable to sheaves having non-metallic bodies formed as one piece articles molded from plastic material.

We claim:

1. A multi-grooved sheave embodying an overhanging or centrally unsupported portion having therein a plurality of the belt grooves of the sheave, the hub and surrounding portion of the sheave and said overhanging portion being in a unitary body composed of wood plies or laminations adhesively joined in planes parallel with the sheave axis, the wood pieces forming the plies or laminations being continuous from end to end of said body.

2. A multi-grooved sheave of the block type comprising a cylindric body composed of wood laminations adhesively joined in planes parallel with the sheave axis and having the grain of the wood disposed longitudinally, said body being formed with annular belt grooves in its periphery and with a central hub bore, the side walls of said grooves being provided by wood surfaces transverse of the grain of the wood throughout the entire circumference.

3. A sheave comprising a cylindric wood body

having an annularly grooved periphery and a central hub bore, a wood bushing fitted therein and adapted to fit and to be keyed to the sheave shaft, means for keying said bushing to said body, and means comprising a nut inset in said body and a radially disposed set screw extending through said nut in threaded engagement therewith and through a hole therefor in said bushing for securing said body to the shaft by clamping the bushing between said shaft and body.

4. A sheave comprising a cylindric body composed of adhesively joined plies or laminations of wood or other suitable non-metallic material, there being recesses drilled in said body parallel with and adjacent to the hub bore and intersecting radial set screw holes, said recesses being of greater diameter than said holes, nuts consisting of cylindrical elements having transverse set screw holes and fitted in said recesses with their holes in line with the set screw holes of said body, and set screws extending through said nuts in threaded engagement therewith whereby to secure said body to the sheave shaft.

5. A sheave comprising a cylindric body of non-metallic material having an annularly grooved periphery and a central hub bore, a non-metallic bushing fitted in said bore and adapted to fit and to be keyed to the shaft to which the sheave is to be applied, said bushing having an internal longitudinal keyway for engagement by a shaft key and an external longitudinal groove angularly spaced from said keyway, correspondingly angularly spaced nuts inset in said body adjacent to said bore and with their holes disposed radially, one of said nuts engaging said groove to key said bushing to said body, and set screws extending through said nuts in threaded engagement therewith and through holes in said bushing for securing said body to the shaft by clamping said bushing therebetween, one of said set screws adapted to bear against said shaft key and the other directly against the shaft.

6. A sheave comprising a cylindric body of non-metallic material having an annularly grooved periphery and a central hub bore, a non-metallic bushing fitted therein and adapted to fit and to be keyed to the sheave shaft, said bushing having an internal longitudinal keyway for engagement by a shaft key and an external longitudinal groove angularly spaced from said keyway, there being correspondingly angularly spaced recesses drilled in said body parallel with and adjacent to said bore, nuts comprising cylindrical metal elements with transverse screw holes fitted in said recesses, the holes thereof being radially disposed, one of said elements engaging said groove for keying the bushing to said sheave body, and radially disposed set screws extending through said elements in threaded engagement therewith and through holes therefor in said bushing whereby to secure said sheave body to the shaft by clamping said bushing therebetween, one of said set screws adapted to bear against said shaft key and the other directly against the shaft.

7. A sheave comprising a non-metallic sheave body, a non-metallic bushing fitted therein and adapted to fit and to be keyed to the sheave shaft, said bushing having an internal longitudinal keyway for engagement by a shaft key and an external longitudinal groove angularly spaced from said keyway, there being correspondingly angularly spaced pluralities of nuts inset in said body adjacent to said bore with the holes of the nuts disposed radially, spacers of non-metallic material

between the nuts of each group, the nuts of one group engaging said groove to key said bushing to said body, and set screws extending through said nuts in threaded engagement therewith and through holes therefor in said bushing whereby to clamp the bushing between the sheave shaft and said body, one group of said screws adapted to bear against said shaft key and in the other bearing directly against the shaft.

8. A sheave comprising a non-metallic sheave body having a central hub bore, there being a recess drilled in said body adjacent to and parallel with said bore, a cylindrical metal element fitted in said recess, and a radially disposed set screw extending through said element in threaded engagement therewith and screwable against the shaft for securing said sheave body thereto, said element being supported against outward thrust

of said set screw solely by the non-metallic material of said body.

9. A sheave comprising a non-metallic sheave body having a central hub bore, there being a recess drilled in said body adjacent to and parallel with said bore, a cylindrical metal element fitted in said recess, and a radially disposed set screw extending through said element in threaded engagement therewith and screwable against the shaft for securing said sheave body thereto, said element protruding laterally into said bore to function as a key for keying to said body a bushing fitted in said bore, said element being supported against outward thrust of said set screw solely by the non-metallic material of said body.
